UNITED STATES PATENT OFFICE.

FRIEDRICH SCHNAPP, OF BERLIN, GERMANY.

WEIR AND THE LIKE.

979,574.

Specification of Letters Patent.

Patented Dec. 27, 1910.

Application filed October 20, 1909. Serial No. 523,692.

To all whom it may concern:

Be it known that I, FRIEDRICH SCHNAPP, a subject of the German Emperor, and residing at Berlin, Germany, have invented certain new and useful Improvements in Weirs and the Like, of which the following is a specification.

My invention relates to weirs and a primary object is to provide improved means for regulating the flow from reservoirs having a variable water-level.

According to my invention I provide a weir from which there leads to the downstream a plurality of outlets or conduits controlled by automatic closure members. For obtaining an approximately constant discharge I arrange said closure members in such manner that when the water-level rises and the velocity of the outflowing water correspondingly increases the outlets are closed automatically in order, with the exception of those which always remain open, and when the water-level falls and the velocity of the outflowing water correspondingly decreases the outlets are opened correspondingly in order. Consequently at the highest water-level the conduits provided with closure members are all closed, so that a desired quantity of water per unit time flows at an increased velocity only through the always open conduits, whereas at lowest water-level all the conduits are open through which the same quantity of water per unit time is discharged at a less velocity.

One illustrative embodiment of my invention is represented by way of example in the accompanying drawing wherein:

Figure 1 is a vertical sectional elevation in the plane A—B in Fig. 3; Fig. 2 is on the left a cross-section in the plane C—D in Fig. 3, and on the right a diagram explained hereinafter; Fig. 3 a diagram showing the general arrangement in plan, and Fig. 4 a top plan view of a cylindrical sliding-valve.

Referring to the drawing and firstly to Fig. 2, the curve X—X can be readily calculated having horizontal ordinates which indicate for every water-level measured on the abscissa Y—Y how large the total outlet must be for the pressure above atmospheric existing under the water-level in question if a definite uniform quantity of water is to be discharged. The outlet must be smaller for higher water-levels than for lower. The total outlet consists of a large number of

smaller outlets *a*, only seven being shown in the present instance for the sake of clearness. These suffice for discharging at the lowest water-level NW of the reservoir the quantity 60 of water required down stream, whereas at the highest water-level HW three openings suffice. Consequently four outlets must be closed in turn at the corresponding water-levels as the water-level rises, and, reversely, 65 can be opened again as the level falls. In the illustrative embodiment these outlets are closed by cylindrical sliding-valves I, II, III, IV movable in guides *g*, but these sliding-valves differ from those of the well-known 70 type in that they comprise two cylindrical shafts *b*, *c* of different diameter, the upper shafts being of different height. The bottom *d* of the top, wider shaft *b* which is open at the top separates this from the 75 lower, narrower shaft *c* which is open at its lower end, said bottom being provided with a small aperture *e*. The diameter of the top shaft *b* is so great that the sliding-valve floats at the lowest water-level NW, its bottom orifice is opened and the interior of the valve remains empty of water on account of the suction produced by the water being discharged.

In the case of the taller sliding-valves III, 85 IV, after the float-like body necessary for making the valve buoyant has been formed, the upper portion may be made narrower as represented in dotted lines in Figs. 1 and 2. In order that the valves may not rise above 90 the height (say $h = \frac{1}{4} d$) necessary for discharging the water, their upward movement is limited by stops or lugs *f*.

Now if the water-level rises from NW and overflows the top edge of valve I, this 95 will fill with water, descend and close its registering outlet or conduit *a*. As the water-level rises further the same occurrences are repeated in the case of valves II, III, and IV as soon as the water-level 100 reaches their top edges. At the highest water-level HW the necessary three outlets alone remain open. By selecting the number of valves and the corresponding heights of their top ends it is possible to approach 105 as nearly to the theoretical line X—X of the cross-sectional area of outflow as is necessary in practice.

When the water-level falls the reverse operations take place. For example, when the 110 falling water-level reaches the top edge of valve IV no more water flows from above

into it, its contents flows through aperture e and the valve rises until its lugs abut against the guide g and the outlet or conduit controlled by the valve is opened. Consequently, the valves are closed and opened automatically, regularly, in order and repeatedly in such manner that a uniform discharge of a definite desired quantity of water passes down stream.

In the above it has been supposed that the discharge is uniform. Obviously the curve $X-X$ may be calculated so that the discharge at higher water-levels is greater than at lower. If it is admissible for industrial working that in the case of larger supplies of water the discharge can be increased considerably, *e. g.* doubled, it is preferable to provide a second cylindrical sliding-valve chamber and to connect it with the first. The connecting sliding-valve may be so arranged that the second chamber allows only a small surplus to be discharged, since the cylindrical sliding-valves in the same also close when the low water-level NW falls below the normal, because the cylindrical sliding-valves then no longer float and only rise gradually into the floating position corresponding to their weight when the water rises. Exceptionally high water must of course be let off as usual by special waste-gates, sluices, and the like.

The guides provided for the valves may be of different forms. For instance, as shown in Fig. 1, said guides are in the form of beams or bars g , I-shaped in cross section, while in the form shown in Fig. 2, a series of rolls g' constitute the guides. As shown in Fig. 4, the guide rolls g^2 are carried in bearings attached to the valve and coöperate with vertical tracks or guide-ways g^3 .

In the above description the cylindrical sliding-valve has been adapted as the closure

member because it is most suitable for the ends in view, since it has to take up no lateral forces, can consequently be guided very easily by means of simple lateral rollers without special mechanical devices, and therefore offers very small resistance to motion. The small lift of the cylindrical sliding-valve is also advantageous.

If the head of water at disposal at the herein-described regulating means is to be utilized by a turbine or other prime mover, my regulating means may be placed directly in the discharge from the turbine.

I claim:—

1. In means for regulating the discharge from reservoirs having variable water-level, the combination, with a weir having a plurality of outlets below the lowest water-level, of a plurality of floats of various height, open above and provided below with an outlet, each of said floats being guided vertically above one of said outlets in the weir and adapted to close the same, when the water-level rises above the float, and to open the same when the water-level subsequently falls below the float.

2. The combination, with a weir having a discharge conduit, of a cylindrical sliding-valve guided vertically above, and adapted to close the mouth of said conduit, said sliding-valve comprising a bottom shaft, a top shaft of larger diameter than the bottom shaft, and a perforated bottom between said shafts, substantially as shown and for the purpose specified.

In testimony whereof, I affix my signature in the presence of two witnesses.

FRIEDRICH SCHNAPP.
